UNITED STATES PATENT OFFICE.

JOHN CHARLES MALSTER, OF STROMSBURG, NEBRASKA.

MEANS FOR REPAIRING WORN RIFLED GUNS.

1,127,268.

Specification of Letters Patent.

Patented Feb. 2, 1915.

Application filed June 14, 1913. Serial No. 773,637.

To all whom it may concern:

Be it known that I, JOHN CHARLES MALSTER, citizen of the United States, residing at Stromsburg, in the county of Polk and 5 State of Nebraska, have invented certain new and useful Improvements in Means for Repairing Worn Rifled Guns, of which the following is a specification.

This invention relates to means for repairing rifled guns and fire-arms of all descriptions.

The primary aim of the invention is to provide a simple means whereby the worn barrel of a gun or fire-arm of any type 15 whatsoever may be provided with a rifled surface, so as to act upon the bullet in equally as efficient a manner as when new. It has been proposed to accomplish this result by various methods, all of which have 20 proved unsatisfactory, however, due in my opinion, to the fact that in carrying out the various methods it is contemplated that the bore of the barrel be rifled for its entire length.

25 By actual experiment I have found that in order to secure the best results and to impart the desired rotation to the bullet it is preferable that the bore of the barrel be rifled only at and adjacent the muzzle end 30 of the barrel. This is no doubt true for the reason that before reaching the rifled portion of the bore the bullet has gained such momentum that it will not be so resisted by the rifling as to have its velocity 35 materially retarded, and the rifling is allowed to act against the surface of the bullet with a cleaner "cut." Another decided advantage accruing from the feature of rifling only the muzzle end of the barrel 40 is that the barrel is much easier to clean and is less likely to become leaded.

For a full understanding of the invention reference is to be had to the following description and accompanying drawing, in 45 which:—

Figure 1 is a vertical longitudinal sectional view through a rifle barrel illustrating the device of the present invention in place therein. Fig. 2 is a vertical transverse sectional view on the line 2—2 of 50 Fig. 1. Fig. 3 is an end elevation of the barrel. Fig. 4 is a perspective view of the muzzle end of the barrel.

Corresponding and like parts are referred to in the following description and indicated in all the views of the accom-

panying drawing, by the same reference characters.

In the drawing the barrel is indicated by the numeral 1 and the barrel illustrated in 60 the drawing is presumed to be a worn one, in which event it would be devoid of well defined rifling, and, in the character of its bore, would more nearly resemble a smooth bore rifle than a rifled one. In preparing 65 the barrel for the insertion therein of the repairing device, embodying the invention, the barrel is bored or reamed out from its muzzle end for a fraction of its length which, in the instance of the ordinary small 70 caliber rifle, may be six inches, more or less. In boring out the barrel, as indicated at 2, a shoulder 3 is formed at the inner end of the bored length. After the barrel has been properly bored in the manner stated, 75 it is interiorly threaded immediately adjacent and at its muzzle end, as indicated at 4. The barrel is now ready for the insertion of the device of the present invention which 80 is to restore it to its normal condition.

The device mentioned above is in the nature of a tube 5, preferably of the same quality of metal as the barrel 1 and of a length equal to the length of the bored out portion of the barrel. The exterior diameter of the tube 5 is such that the tube will 85 exactly fit within the muzzle end of the barrel with the interior end of the tube resting against the shoulder 3, in the manner shown in Fig. 1 of the drawing. The 90 bore of the tube is of the same diameter as the bore of the barrel at the breech-end, so that the surfaces of the bores of the barrel and tube, respectively, merge at the inner end of the tube, and no obstruction is 95 offered to the free passage of the bullet through the barrel.

The tube 5 is exteriorly threaded as indicated by the numeral 5', and after the unthreaded portion of the tube has been fitted 100 into the bore of the barrel the tube is rotated so that its outer end will be threaded into the outer end of the barrel, by inserting the fingers of a suitable spanner wrench (not shown) into sockets 6 formed at diametrically opposite points in the said outer end of the tube 5. It will be observed that the outer end of the tube is flush with the outer end of the barrel when the tube is 105 properly positioned within the barrel. The tube 5 has the surface of its bore rifled, as indicated at 7 and it is ob-

vious that the rifling within the tube 5 may be of any of the several types. Not only may the tube 5 be readily fitted into the barrel prepared for its insertion, but it may, 5 when it is desired to clean the tube, be removed so that the cleaning operation may be readily and conveniently accomplished.

It will be apparent from an examination of Fig. 1 of the drawings that the bullet 10 passing through the barrel will for the major length of its barrel-travel contact with a smooth surface and its velocity when it reaches the inner end of the tube 5 will be such that its speed of travel will not be materially retarded by the rifling within the tube, but on the other hand the rifling will act with a smooth "cut" upon the surface of the bullet, and it will not be likely that the tube or the barrel will become leaded, 15 20 after repeated firing.

It is to be distinctly understood that the tube may be of any length found suitable for the purpose or best adapted for the particular type of gun for which it is designed. 25 It is also to be noted that the caliber of the rifle is in no way altered by the use of the tube herein described, nor will be its accuracy if the tube is properly fitted within the barrel.

30 Having thus described the invention what is claimed as new is:—

1. The combination with a firearm barrel, the rifling of which is worn and the bore of which at the muzzle end thereof has 35 been enlarged and provided with internal threads at its muzzle extremity and an internal annular shoulder at a point inwardly remote from said threads, of a rifled tube equal in length to and inserted in the enlarged portion of the bore of the barrel with 40

its inner end fitting against the internal annular shoulder and provided at its outer end with external threads to engage the internal threads at the muzzle extremity of the barrel, the inner surface of the tube being 45 flush with the inner surface of the barrel and the external diameter of the tube being substantially equal to the diameter of the enlarged portion of the bore of the barrel, the outer terminal of the tube being flush with 50 the terminal of the barrel.

2. The combination of a firearm, the rifling barrel of which is worn and the bore of which at the muzzle end has been enlarged and provided with internal threads at its 55 muzzle extremity and an internal annular shoulder at a point inwardly remote from said threads, said enlarged portion of the bore being of uniform diameter throughout its length, of a rifled tube, equal in length 60 to the enlarged portion of the bore, inserted in the said enlarged portion and arranged with its inner end fitting against the internal annular shoulder and its outer end flush with the outer end of the barrel, and external 65 threads formed adjacent the outer terminal of the tube for engagement with the internal threads of the enlarged portion of the bore, the wall of the tube being of uniform thickness and external diameter throughout its 70 length except at the threaded portion which is of greater external diameter than the other portion of the tube.

In testimony whereof I affix my signature in presence of two witnesses.

J. CHARLES MALSTER. [L. s.]
